US0D1041868S

(12) United States Design Patent (10) Patent No.: US D1,041,868 S
(45) Date of Patent:  Sep. 17, 2024

(54) SHOE

(71) Applicant: NIKE, Inc., Beaverton, OR (US)

(72) Inventor: Justin Amago, Portland, OR (US)

(73) Assignee: NIKE, Inc., Beaverton, OR (US)

() Term: 15 Years

(21) Appl. No.: 29/863,247

(22) Filed: Dec. 16, 2022

(51) LOC (14) Cl. 02-04

(52) U.S. Cl.

USPC D2/919

(58) Field of Classification Search

USPC D2/902–912, 916–926, 969–978

CLAIM

The ornamental design for a shoe, as shown and described.

DESCRIPTION

FIG. 1 is a front perspective view of a shoe showing my new design;

FIG. 2 is a side view thereof;

FIG. 3 is an opposite side view thereof; and,

FIG. 4 is an opposite side front perspective view thereof. The broken lines immediately adjacent to the photographic area define the bounds of the claimed design and form no part thereof. The broken lines depicting the remainder of the shoe form no part of the claimed design.

1 Claim, 4 Drawing Sheets
